secured together and radiate from a central ring 26, said ring 26 being adapted for placement over the top or main stem 28 of tree 22. One end of each longitudinal strip 24 is provided with fastening means, such as hook 29, which is adapted to be engaged around ring 26 and to thereby support the longitudinal backing strip 24.

The longitudinal backing strip 24 is preferably made of synthetic plastic, e.g. polyvinylchloride, and may be gold colored. However, cord, wire, chain or other lightweight durable material having a variety of desired colors, may also be used. The use of synthetic plastic for the longitudinal backing strips 24 will conveniently permit joining of several strip segments to extend the length thereof or joining two strips together at their point of intersection, by means of heat sealing, stapling, gluing, etc.

To complete the covering 20, a plurality of garland segments 30 are attached to and draped transversely between two respective longitudinal backing strips 24; the garland 30 may additionally be attached to and along the longitudinal backing strips 24. Alternatively, the garland 30 may be used as the longitudinal backing strips 24.

The garland 30 is comprised of a wreath, festoon, chain of flowers, tinsel, etc. In the preferred embodiment, a tinsel garland is used which is constructed of metallic yarn wrapped around a core of cotton, cotton wire, silk, rayon, etc., having radiating finger-like threads, copper plated, to produce a glittering golden color (see FIG. 4). The garland 30 is draped in pendulous manner between each of two respective longitudinal strips 24 by means of staples, or other appropriate fastening means at intermediate locations 32 therealong. The garland 30 may also be affixed longitudinally along the backing strips 24 and may also be used for the longitudinal strips 24.

The so formed, tent-like covering 20 will be basically conical in shape and flexible enough in its radial direction to permit accommodation over trees 22 having various sizes. It should of course be noted that the covering 20 will be supported both by the main stem 28 passing through the central ring 26 and by the branches of the tree extending outwardly and engaging the longitudinal backing strips 24 and garland 30.

In an alternate embodiment shown in FIG. 3 a tree covering 20a is provided with fastening means comprised of a plurality of hooks 34 and eyelets 36, although a single, flexible plastic piece to hold the two strips together could be used as a fastener. In a preferred embodiment, the hooks 34 are fastened to a longitudinal backing strip 24a and the eyelets 36 are attached to a longitudinal backing strip 24a' having garland 30a thereon. The tree covering 20a of this modified embodiment can be wrapped around a tree instead of being lowered over the tree as is the case for the covering 20 shown in FIG. 2. The hooks 34 and eyelets 36, as shown in FIG. 4, are attached to a band 38, 38', said band being affixed to the longitudinal backing strip 24a and 24a'. The band 38, 38' also hold the adjoining garlands 30, 30a.

In another embodiment, a decorative tree covering 20b encompasses two separate and integral half-sections 40. The half-sections 40 are adapted for mating engagement and each section contains longitudinal backing strips 24b, 24b', in this embodiment; garland is used for the backing strips, and transverse garlands 30b are attached thereto. On each of the half-sections 40, are provided in the respective sets of hooks 34b and eyelets 36b. A cone shaped mounting fixture 42 is used for suspending the longitudinal backing strips 24b over the tree. The mounting fixture 42 is hollow and adapted to be placed over a main stem 28b of the tree and is further provided with an annular portion 44 which will accept a plurality of angular fasteners 46 attached to the ends of each of the longitudinal backing strips 24b, 24b' and will thus hold longitudinal backing strips 24b, 24b' together and support the attached garlands 30b. Besides fastening the two sections by hook and eyelets assemblies, the two sections could be joined by single fastener, such as a hog ring, etc.

It should be apparent that the pre-designed garland patterns may be varied and FIGS. 7 and 8 show a modified arrangement and method of attaching the garland 30c in a polygonal fashion. In this embodiment, the garland 30c serves as its own backing strips and a continuous strip of garland 30c is positioned over the plurality of crossing garlands 30c and attached to each other by means of a staple fastener, hog ring 56, or like device (see FIG. 8). The garland strips 30c as shown in FIG. 7 are designed to form a polygonal pattern.

FIGS. 9, 10 and 11 illustrate further embodiment which encompasses the use of a network web including a plurality of longitudinal backing strips 24d and a plurality of transverse and intersecting transverse backing strips 48. The backing strips 24d and 48 are joined at their points of intersection 50 by appropriate fastening means such as welding, gluing, stapling, heat sealing, etc. The longitudinal backing strips 24d are secured together with angular fasteners 46 adapted for engagement around a central ring 26d. The ring 26d is placed over a main stem 28d of the tree and will thereby support the web network so formed. The garlands 30d may be draped in a pendulous manner and affixed to the backing strips 24d and 48 in a manner similar to that described with respect to the other embodiments. Additionally, this embodiment entails the use of a bow 52 or other adornment affixed to the web network and as illustrated in this case may be attached at the point 50 of intersection between the backing strips 24d and 48. Bows 52 may be attached by means of a pliable wire or clip and can additionally secure the longitudinal backing strip 24d to the transverse backing strip 48.

It should be noted that the above cited embodiments are intended as exemplary, and while they have described the invention with specific implementation thereof, other modifications, and changes might be made in the embodiment so set forth and will be apparent to those skilled in the art.

Furthermore, it should be understood that all materials herein described or shown in the accompanying drawings are to be interpreted as illustrative and not in a limiting sense.

What is claimed is:

1. A decorative tree covering for ornamentation purposes comprising a plurality of backing strips, said means further being adapted for attachment to the top of a tree, and a plurality of garlands fastened to said longitudinal backing strips in a predesigned pattern; said tree covering is formed as two half-sections, said half-sections being provided with a plurality of fastening members and corresponding other fastening members for interlocking engagement when the covering is in place around a tree, and further includes a hollow cylindrical mounting fixture for securing the longitudinal backing strips.

2. A decorative tree covering as claimed in claim 1, wherein one end of said backing strips is attached to a central ring member, said ring member being adapted for placement over a main stem at the top of a tree.

3. A decorative tree covering as claimed in claim 2, wherein the garlands are pendulously draped between each of two longitudinal backing strips in the predesigned pattern, said longitudinal backing strips also being garland.

4. A decorative tree covering as claimed in claim 3, wherein the longitudinal backing strips are made of synthetic plastic, and the garlands are tinsel.

5. A decorative tree covering as claimed in claim 1, wherein the tree covering is provided with an opening along a longitudinal strip to permit the covering to be wrapped around a tree and said longitudinal backing strip secured by fastening means along said opening when the covering is in place around a tree.

6. A decorative tree covering as claimed in claim 1, wherein said mounting fixture is adapted for placement over a main stem at the top of a tree, said mounting fix-

ture being further provided with an annular rim for securing the ends of said longitudinal backing strips.

7. A decorative tree covering as claimed in claim 4, wherein the garlands are draped in a polygonal pattern and are affixed to each other by staple fasteners. 5

8. A decorative tree covering as claimed in claim 4, further including a plurality of transverse backing strips joined to the longitudinal backing strips at points of intersection and thereby forming a web network.

9. A decorative tree covering as claimed in claim 8, 10 wherein the web network is embellished with garlands and further adorned with bows affixed at the points of intersection between the longitudinal and transverse strips and further securing the strips at said points.
